MAGNETIC LIFT FOR ELECTRODES IN ELECTRIC OSCILLATORS.

1,142,496.

Specification of Letters Patent.

Patented June 8, 1915.

Application filed April 29, 1913. Serial No. 764,357.

To all whom it may concern:

Be it known that I, ALFRED H. COHEN, a citizen of the United States, residing at Fruitvale, in the county of Alameda and State of California, have invented new and useful Improvements in Magnetic Lift for Electrodes in Electric Oscillators, of which the following is a specification.

This invention relates to an apparatus for automatically lifting and separating the electrodes in an electric oscillator by means of electromagnetism.

The object of this invention is to provide an electric, automatic mechanism for the purpose of simultaneously lifting a plurality of electrodes in an oscillating circuit, and also for the purpose of adjusting the spacing between the electrodes where several electric oscillators are installed in a circuit.

The invention consists of the parts and the construction and combination of parts as hereinafter more fully described and claimed, having reference to the accompanying drawings, in which—

Figure 1 is a side elevation in section showing the application of the invention. Fig. 2 is a front view, partly in section, and a diagram showing the position of the mechanism with relation to the several apparatus used in wireless transmission.

In the operation of a number of high frequency oscillators it has been found that in order to produce uniform persistent undamped oscillations of high frequency, force and effect it was absolutely necessary that the electrodes in each oscillator should be provided with separate or independent adjustments for the purpose of adjusting the space between the electrodes in each separate oscillator. This is of great importance as it is otherwise practically impossible to produce synchronism of oscillation between the several oscillators in a circuit. The elimination of such independent adjustment between the electrodes will generally produce irregular oscillations which become quickly damped with a consequent loss of efficiency, and without an independent adjustment it can be seen by the eye that all the oscillators are not working alike; *i. e.* the sparking between the electrodes in each oscillator is different, and this can only be remedied by an independent adjustment, as it is found by observation and practice that each oscillator requires a different distance between the electrodes.

Referring to the drawings: A and B indicate the containers of a pair of submerged oscillators connected in series, and C and C' indicate a pair of stationary rectangular-shaped, vertically disposed supporting frames adapted to be secured to the edges of the containers by any suitable means, or as here shown, by a pair of downwardly extending clamps 2 and 2' and screws 3.

Centrally and vertically mounted within the containers A and B is a pair of stationary electrodes 4 and 5 and a pair of movable, adjustable electrodes 6 and 7. The electrodes 6 and 7 are secured on the lower ends of a pair of downwardly extending square-shaped rods 8 and 9, slidably mounted in the supporting frames C and C', while the stationary electrodes 4 and 5 are shown as consisting of hollow metal cylinders supported on the outer ends of a pair of tubes 10 and 11 forming the terminals of a pair of cooling coil frames 12 and 12', which in turn are secured to the clamps 2.

As before stated, the object of this invention is to provide an automatic lifting mechanism, whereby several electrodes may be lifted in unison and whereby the spacing between the electrodes may be independently adjusted. This is accomplished by the following mechanism: Slidably mounted within the main supporting frames C and C' is a pair of secondary sliding frames 13 and 13', in which are mounted a pair of clutching magnets 14 and 14', the cores 15 and 15' of which are sufficiently elongated to project through the frames 13 and 13' and slots 16, formed in that portion of the main supporting frames C and C' in which the rods 8 and 9 are slidably mounted, to bring the cores into contact with the rods.

Adjustably secured in the upper portions of the supporting frames is a pair of lifting magnets 17 and 18, and suitably secured on the top portions of the slide frames 13 and 13' is a pair of armature plates 19 and 19', which are so positioned as to be attracted by the cores of the lifting magnets when these are energized; the distance lifted being controlled by the adjusting screws 20 and 20'. The several magnets 14—14' and 17—17' are connected in series on one circuit and will, therefore, be energized simultaneously, causing the clutching magnets 14 and 14' to grip the square-shaped rods 8 and 9, while the lifting magnets, when energized, will be caused to attract the arma-

ture plates 19 and 19' and lift the frames 13 and 13', together with the rods 8 and 9 secured by the clutching magnets 14 and 14'; the lift or spacing between the several electrodes being independently controlled by the adjusting screws 20 or 20'. It thus becomes possible to adjust the spacing between the electrodes, after the oscillating circuit has been closed, by raising or lowering the lifting magnets by their adjusting screws until synchronism of oscillation has been produced between the several oscillators.

The electrodes 6 and 7 in common practice are generally formed of carbon and will gradually burn away or shorten by the corrosive action of the arc or spark between the electrodes, so that the carbon electrodes in one oscillator may become shorter than in the other, thereby interfering with and decreasing the efficiency and constancy of the oscillations. This would thus destroy the adjustment previously secured by adjusting the lift of the lifting magnets, but may be instantly remedied by simply opening the circuit which will allow the carbon electrodes to instantly drop into contact with the stationary electrodes, being released the moment the clutching magnets 14 become deenergized. The closing of the circuit through the several magnets will again energize the clutching magnets with connected coöperating lifting magnets and cause the electrodes to be elevated into the position previously secured by adjustment. It is thus possible, once a desirable and efficient adjustment has been secured, to maintain this, as it is only necessary to allow the carbons to return into contact with the stationary electrodes and again be elevated to secure such an adjustment.

While I have here shown the lifting and adjusting mechanism as used in connection with oscillators submerged in imperfectly conducting liquids, I wish it understood that it is also applicable to any of the well-known types of oscillators. The tubular frames 12 and 12' supporting the stationary electrodes 4 and 5 consisting of hollow tubing, may be advantageously employed both for the purpose of supplying a cooling medium for the lower stationary metal electrodes, and also for the purpose of forming an electrical conductor to same, connection being secured by simply attaching one terminal to the screw, as indicated at 21, Fig. 1. I have also shown the front portions of the main supporting frames C and C' as being provided with hinged sections 22, provided for the purpose of securing the rods 8 and 9 in their guide pockets. These may be swung about their hinges 23 into the dotted line position, indicated at 24, to permit the removal of the carbon supporting rods 8 and 9 at any time without disturbing the remainder of the apparatus.

The apparatus here shown is simple and compact in construction and may be easily removed as a unit at any time by releasing the clamping screws. The materials and finish of the several parts of the mechanism are such as experience and judgment of the manufacturer may dictate.

Having thus described my invention, what I claim and desire to secure by Letters Patent is:

1. The combination in a high frequency oscillator, of a plurality of stationary electrodes, a plurality of electrodes mounted to move in relation to the stationary electrodes, rods to which the movable electrodes are secured, supporting frames in which the rods are slidably mounted, lifting frames slidably mounted within said frames, clutching magnets adapted to engage the rods mounted in said lifting frames, armature plates secured to the lifting frames, lifting magnets mounted with relation to said armature plates, means for energizing the several magnets in unison, and means for adjusting the position of the lifting magnets with the supporting frames.

2. In combination with a movable and stationary electrode, means to grip the movable electrode, means to raise the gripping means, and means which when moved to one position simultaneously renders the gripping means operative and raises the same to thereby separate the electrodes and to maintain same stationary, regardless of the space between the electrodes and which in another position releases the gripping and raising means to enable the movable electrode to instantaneously contact with the stationary electrode to thus allow automatic readjustment of the predetermined space between the electrodes upon shortening of the movable electrode.

3. In an oscillator having a pair of spaced electrodes, releasable means to grip one of the electrodes and to move same away from the other electrode, said means acting automatically to grip the movable electrode at any position of the latter when rendered operative and to maintain same stationary regardless of the space between the electrodes and when released to allow the movable electrode to instantaneously engage the other electrode to thus allow automatic readjustment of the predetermined space between the electrodes upon shortening of one of same.

4. In an oscillator having a movable and a stationary electrode, energizable means operating independently of the space between the electrodes included in a circuit to engage and raise the movable electrode at any position of the latter whereby upon opening of the circuit said means releases the movable electrode and allows same to instantaneously engage the stationary elec-

trode and upon closing of the circuit again engages and lifts the movable electrode whereby the predetermined extent of separation of the electrodes may be automatically maintained by mere manual opening and closing of the circuit at will.

5. In an oscillator having a movable and a stationary electrode, means operating independently of the space between the electrodes to releasably engage and raise the movable electrode and means manually operable at will to enable upon shortening of the movable electrode release and reengagement of the movable electrode to allow the latter upon release to instantaneously engage with the stationary electrode.

6. In an oscillator having a movable and a stationary electrode, a main frame having means to guide the movements of the movable electrode, a supplemental frame slidable in the main frame, a magnet borne by the supplemental frame to attract and hold the movable electrode, a magnet adjustably carried by the main frame to attract the supplemental frame, said magnets being electrically connected whereby upon closing of the circuit the movable electrode will be gripped and raised with the supplemental frame, and upon opening of the circuit the electrode will be released and with the supplemental frame gravitate to lowermost positions.

7. In combination with a plurality of stationary and movable electrodes, selectively operated automatic means for gripping and releasing the movable electrodes in any position of the latter, means for lifting the gripping means to thereby raise the movable electrodes, and means for independently regulating the extent of movement of each of the gripping means.

8. In combination with an oscillator having a movable and a stationary electrode,

means operating independently of the space between the electrodes for lifting the movable electrode by engagement therewith at any point on the electrode which aligns with said lifting means to sustain the movable electrode stationary, and means operable at will whereby when the electrode shortens same may be allowed to move into engagement with the stationary electrode and be subsequently again and automatically engaged with the lifting means.

9. In combination with the stationary and movable electrodes of an oscillator, energizable means operating independently of the space between the electrodes to engage the movable electrode to enable raising of the latter and to sustain same stationary and which upon deenergization thereof releases the movable electrode to allow the latter to move in to engage with the stationary electrode, and manually controlled means to effect raising and lowering of the energizable means and to control energizing and deenergizing of the energizable means at will.

10. In combination with the stationary and movable electrodes of a plurality of oscillators, means to automatically grip the movable electrodes to enable raising thereof, means to enable release of said gripping means at will and reengagement at a different point on the electrode, means to raise the gripping means, and means to enable independent adjustment of the extent of movement of each of the gripping means.

In testimony whereof I have hereunto set my hand in the presence of two subscribing witnesses.

ALFRED H. COHEN.
